FENCE RAIL CONNECTION

Filed Dec. 30, 1929

Fig. 2 -

UNITED STATES PATENT OFFICE

WALLACE S. RICH, OF COVINGTON, KENTUCKY, ASSIGNOR TO THE STEWART IRON WORKS COMPANY, OF COVINGTON, KENTUCKY, A CORPORATION OF KENTUCKY

FENCE RAIL CONNECTION

Application filed December 30, 1929. Serial No. 417,478.

It is the object of my invention to provide a new and improved fence comprising posts of novel cross-section for compactness of construction, maximum strength and pleasing appearance; further, to provide a fence comprising posts formed with webs extending lengthwise thereof and perpendicular to the plane of the fence and having oppositely extending flanges at each edge of the web, and a rail extending lengthwise of the fence of a cross-section similar to the cross-section of the posts, the webs of the posts provided with openings of similar cross-section through which the rail extends and in which the rail is arranged to have a horizontal position or positions at various angles to the horizontal in the plane of the fence; and, further, to provide novel connecting means between the ends of the rail and the end posts.

It is the object of my invention, further, to provide novel construction of posts which are substantially of I-beam form in cross-section and have upper portions which are bent into overhanging relation to the main upright portions of the posts and are integral with the latter; and, further, to provide posts which are of substantial I-form in cross-section, the outer surfaces of the flanges thereof being rounded for increasing the cross-sectional area of the posts and modifying the side edges thereof to avoid sharp corners.

The invention will be further readily understood from the following description and claims, and from the drawings, in which latter:

Fig. 1 is a perspective view of a portion of a fence embodying my invention.

Fig. 2 is an enlarged perspective view of the same, partly broken away.

Fig. 3 is a vertical section of the same, taken on the line 3—3 of Fig. 2, and partly broken away.

Fig. 4 is a horizontal section, taken on the line 4—4 of Fig. 2, showing the connecting means between the end of the rail and the end post.

Fig. 5 is a vertical section showing the connecting means between the butt ends of rail sections, taken on the line 5—5 of Fig. 2.

Fig. 6 is a horizontal section of a detail,

taken on the line 6—6 of Fig. 2, showing means for securing the wire fabric to the rail.

Fig. 7 is a vertical section of the same, taken on the line 7—7 of Fig. 6.

Fig. 8 is a cross-section of a detail showing the connecting means between the upper wire and the overhanging portion of the post, taken on the line 8—8 of Fig. 2.

Fig. 9 is a bottom view of the same; and

Fig. 10 is a side elevation of a blank for the post showing portions to be removed in forming the post.

The post of my improved device is exemplified at 11. The upright portion of the same is of general I-form in cross-section, comprising a web 12 and double flanges 13, 14, extending from the sides of the web at the respective edges of the web. The outer faces of these flanges are rounded, as shown at 15, for increasing the cross-sectional dimensions of the middle portions of the connected double flanges in the plane of the web, whereby a compact structure is formed, the structure having extreme strength and rigidity, and whereby the outer edges 16 of the flanges are rounded so as to avoid sharp corners, thereby preventing injury by contact therewith of humans and animals, and providing a post which may be of unusual height and at the same time be rigid and resist bending stresses in all directions.

At the top of the post there is an overhanging portion 21 which is preferably formed integral with the upright portion of the post, as by removing a triangular section 22, as indicated in dotted lines in Fig. 10, this triangular section including a portion of the web 12 and of the oppositely extending double flange 13 at one side of the web, the opposite double flange 14 being bent so as to cause a meeting of the walls 23, 24, of the recess formed by removal of said triangular section 22, the said walls being butted upon each other and the said butted edges 25 being welded together, as indicated at 26, whereby said overhanging slanting portion 21 is integral with the upright portion of the post.

A rigid structure is formed by bending the

non-severed double flange 14 and welding the abutting edges between the double flange 13 at the opposite edge of the wedge.

In order further to provide a neat appearance for this overhanging portion, the under double flange thereof is partially removed, for instance along the margins 28, and the upper overhanging portion of said double flange and lower portion of the web are removed along the slanting line 29, for forming said overhanging portion tapering toward its upper outer end, and, at said portion, providing the web, and the flanges at the upper edge of the web which extend laterally at both sides of the web. The overhanging portion is also formed to taper upwardly by removing portions of the oppositely extending flanges of the upper double flange along the slanting lines 30.

A rail 31 is provided which is also of substantially I-form in cross-section, and comprises a web 32 and oppositely extending double flanges 33, 34, extending from the respective sides of said web at both edges thereof, the middle portions of said double flanges being formed thicker and rounded, as at 35, for increasing the metal thereof in the plane of the web, and forming a rail of compact form and strong construction. (See Figs. 3 and 5). The outer edges of said flanges are rounded outwardly in cross-section, as shown at 36, for avoiding sharp corners for preventing injury to humans and animals.

The sections of the rail are made in desirable lengths, but as these fences are in practice usually quite long and longer than the length of a rail section, the proximate butt ends of rail sections are connected by providing a sleeve 41 provided with a recess having a cross-section similar to the cross-section of the rail, the sleeve being received about the abutting ends of the proximate rail sections.

The sleeve 41 is preferably made in two sections, divided along the parting lines 42, and are presented oppositely toward each other at said abutting ends. (See Figs. 2 and 5). The sleeve sections have inwardly extending walls 43 received in the grooves 44 at the respective sides of the rail sections, the sleeve sections being provided with recesses 45 in which the respective flanges of the rail sections are received.

A connecting bolt 46 is received through holes in said sleeve sections and between the proximate ends of the rail sections, a nut 47 threaded over said bolt clamping the parts together. The head of the bolt and the nut are received in the grooves 48 extending lengthwise of the sleeve.

The upper portion of the post is provided with an opening 51 of substantially I-form, corresponding substantially to the cross-sectional form of the rail. (See Figs. 2 and 3). This opening comprises a central slot 52 and cross-slots 53, 54, respectively at the upper

end and at the lower end of said upright slot. The middle portions of the upper wall of the slot 53 and of the lower wall of the slot 54 are hollowed away from the vertical slot, forming rounded walls 55, which conform substantially to the cross-sectional form of the outer faces of the mating flanges at the respective edges of the web of the rail 31.

The upper and lower walls of the laterally extending slots respectively are separated sufficiently to form laterally extending slots which in height are greater than the heights of the laterally extending double webs of the rail, in order that the rail may be placed in said slot not only horizontally but at various angles to the horizontal. With this construction, when a fence is built on sloping ground, the posts may be placed vertically in the ground and the rail may be located in the openings and have sufficient play therein so that the rail may be placed at various angles to the vertical posts to arrange the rail in parallelism with the ground.

A strap 58 is received about the periphery of the end post in the horizontal plane of the rail, and is provided with flanges 59 extending lengthwise of the proximate end of the rail and received in the side grooves 44 of the rail. (See Figs. 2 and 4). A bolt 60 is received through complementary holes in said flanges and in the web of the rail, a nut 61 being received about the threaded end of said bolt for clamping the parts in position.

The rail opening may be omitted from the end post so as to permit the end of the rail to butt firmly against the web of the end post, the strap 58 fastening said butt end of the rail in such position and preventing relative movement between the post and the rail lengthwise of the rail in both directions.

The flanges 14 of the post are provided with mating holes 64, these holes being preferably arranged in groups, for instance of four in a group, and the groups being arranged in spaced-apart relation at different points in the height of the post.

Woven wire fabric, exemplified at 65, is secured to the posts and to the rail, for closing the space between posts and under the rail. (See Figs. 2 and 3).

The fabric is secured to the posts by means of clips 66 which may be in the form of wire loops respectively received across wires of the wire fabric and passing through diagonally opposite given ones of the holes, the ends of the wires being bent respectively up and down lengthwise of the post, as shown at 67, for securing the parts together.

The rail and the wire fabric are secured together by means of clips 72 extending across the upper wall of the rail. (See Figs. 2, 6 and 7). The clip is provided with a forward hook-end 73 received through the mesh of the wire fabric and hooking across

the wire thereof. The opposite end of the clip is bent across the rear edge of the upper double flange of the rail, as shown at 74.

Strands 75 of wire, preferably barbed wire, are stretched across and between the overhanging upper portions of the posts. (See Figs. 2, 8 and 9). The respective flanges of these overhanging portions are provided with holes 76, arranged in groups

10 at different points in the length of said overhanging portions, the holes of the respective groups being preferably at the respective sides of the web of said overhanging portion, and diagonally arranged with relation to the web. The wire 75 is preferably received across the overhanging portion of the post between the holes of a group of holes, and secured in place by a clip 77 placed diagonally with reference to the wire, and the respective ends of the clip being received through the holes and bent upon the lower faces of the slanting flanges of said overhanging portions, lengthwise of said overhanging portions as shown at 78.

25 My improved fence is of simple construction, of few parts and is exceptionally compact and rigid. It is further of pleasing appearance.

Having thus fully described my invention, 30 what I claim as new, and desire to secure by Letters Patent, is:

1. In a fence, the combination of a post of substantially I cross-section the middle portions of the double flanges at the respective edges of the web of which are bulged outwardly in the plane of said web, and said post having side upright grooves opening in the direction of the plane of the fence, a rail of similar cross-section having side upright 40 grooves opening perpendicular to the plane of the fence, the end of said rail received in one of the grooves of said post, and a strap about said post, the respective ends of which are provided with flanges located in said respective grooves in said rail, and means securing 45 said flanges to the web of said rail.

2. In a fence, the combination of a post of substantially I cross-section, and a rail of similar cross-section, said post and said rail 50 each having a groove in each side thereof forming the web and the double flange at each edge of said web in said post and in said rail respectively, the web of said post having a substantially I opening extending 55 in upright direction, said rail received in said opening with the height of said rail extending in upright direction in said post, the web of said post at each side of said opening provided with a tongue, said tongues projecting toward each other, and forming laterally projecting spaces above and below 60 said tongues, one of said tongues located in each of said grooves in the respective sides of said rail, and said I opening including 65 its said laterally projecting spaces in said

post being of greater height than the height of said rail and its said double flanges for locating said rail horizontally and at an angle to the horizontal in said opening.

In testimony whereof, I have hereunto 70 signed my name.

WALLACE S. RICH.
